CLAIM

I claim the ornamental design for a multi-purpose ratchet pipe plier, as shown and described.

DESCRIPTION

FIG. 1 is a front side perspective view of a multi-purpose ratchet pipe plier showing my new design;

FIG. 2 is a front view thereof;

FIG. 3 is a rear view thereof;

FIG. 4 is a top view thereof;

FIG. 5 is a left view thereof;

FIG. 6 is a right view thereof; and,

FIG. 7 is a front view of a multi-purpose ratchet pipe plier showing the use state.
